United States Patent Office.

EDWARD FOSTER, OF BOSTON, MASSACHUSETTS.

Design No. 3,857, dated February 22, 1870.

DESIGN FOR A LAMP-CHIMNEY.

The Schedule referred to in these Letters Patent and making part of the same.

To all persons to whom these presents may come:

Be it known that I, EDWARD FOSTER, of Boston, of the county of Suffolk, and State of Massachusetts, have invented a new, useful, and ornamental Design for a Lamp-Chimney; and do hereby declare the same to be fully described in the following specification, and represented in the accompanying drawing, of which—

Figure 1 is a front elevation;
Figures 2 and 3, vertical sections; and
Figure 4, a side elevation of it.
Figure 5 is a top view;
Figure 6, a bottom view of it.

In such drawing, the base part A of the chimney is represented as a short cylindrical tube, from which springs upward a tubular quadrilateral body, B, it being rectangular or thereabouts, in horizontal section, and having in its front face a sunken space or pannel, *a*, surrounded by a projecting fillet, *b*.

The front and rear parts of the body are continued

parallel to each other, or about so, to a circular mouth or top, *c*, to which the sides are continued by being tapered upward in manner as represented.

The sunken panel is for the reception of a mirror or a metallic plating, to form, with the front side of the glass body of the chimney, a reflecting surface or mirror.

The tubular base is joined to the front and rear faces of the body, by curved segments *d d*, the chimney when complete having the form of the design as represented and being both useful and ornamental.

I claim as my invention—

The design for a lamp-chimney, substantially as represented in the accompanying drawing, and as hereinbefore described.

EDWARD FOSTER.
